UNITED STATES PATENT OFFICE.

WILLIS L. JOHNSON, OF SEYMORE, INDIANA.

DESIGN FOR A COAT-FORM.

SPECIFICATION forming part of Design No. 33,709, dated December 11, 1900.

Application filed November 14, 1900. Serial No. 36,529. Term of patent 7 years.

To all whom it may concern:

Be it known that I, WILLIS L. JOHNSON, residing at Seymour, in the county of Jackson and State of Indiana, have invented and produced a new and original Design for Coat-Forms, of which the following is a specification, reference being had to the accompanying drawings, forming part thereof, in which—

Figure 1 is a side view of a coat-form, showing my new design. Fig. 2 is a front edge view thereof, and Fig. 3 is a sectional view on about line 3 3 of Fig. 1.

My design is shown as embodied in a coat-form which is provided at its upper or neck portion with an upwardly-projecting flange or lip A, whose upper edge is shown as curved to form a continuation of the upper front edge of the form, while its rear edge is formed

slightly in advance of the rear edge of the coat-form.

The coat-form rounds up gradually toward a crown-like portion B, which is flat upon its upper surface, as will be understood from Figs. 1 and 2.

Having described my invention, what I claim as new, and desire to secure by Letters Patent, is—

The design for a coat-form as herein shown and described.

In testimony whereof I have signed my name to this specification in the presence of two subscribing witnesses.

WILLIS L. JOHNSON.
